UNITED STATES PATENT OFFICE.

HENRY MILTON FETTERS, OF LAPORTE, INDIANA.

APPLIANCE FOR CLEANING TARNISHED METALS.

1,092,985.

Specification of Letters Patent. Patented Apr. 14, 1914.

Application filed December 18, 1912. Serial No. 737,579.

To all whom it may concern:

Be it known that I, HENRY MILTON FETTERS, a citizen of the United States, residing at Laporte, in the county of Laporte 5 and State of Indiana, have invented a new and useful Appliance for Cleaning Tarnished Metals, of which the following is a specification.

The present invention relates to an appliance for cleaning tarnished metal articles.

One of the objects of the present invention is to provide a battery element of novel or unique construction.

Another object of this invention is to provide a novel appliance of the nature indicated which shall be as simple, durable, compact and inexpensive as possible, consistent with the maximum of efficiency.

This invention also contemplates the production of an appliance of the character indicated which may be readily cleaned or scoured so as to remove the deposit or coating thereon due to the electrolytic action incident to the use of the appliance, and which may be readily handled or manipulated.

With the foregoing and other objects in view which will appear as the description 30 proceeds, the invention resides in the combination and arrangement of parts and in the details of construction hereinafter described and claimed, it being understood that changes in the precise embodiment of invention herein disclosed can be made without in the scope of what is claimed without departing from the spirit of the invention.

The invention has been illustrated in its preferred embodiment in the accompanying 40 drawing, wherein:—

Figure 1 is a bottom view of the appliance, parts being broken away. Fig. 2 is a sectional view thereof, as in use.

The improved appliance comprises two 45 plates of suitable sheet metal, one being preferably fashioned from aluminum, and the other being preferably fashioned from zinc, whereby the aluminum and zinc plates will be electro-negative and electro-positive with 50 respect to one another, although, jointly, the two plates will form an electro-positive or anode. These plates may be of various contours and proportions, the same being illustrated as circular or in the form of 55 disks. These plates or disks are secured to

gether at their peripheries, one plate, preferably the aluminum one, having a peripheral flange 5 bent over the periphery of the other or zinc plate 4.

A ring or annulus 6 of any suitable metal 60 or material is disposed between the peripheries of the disks or plates so as to space them apart, and it is preferable to dish or concave the zinc plate 4, in order that when the device is placed on the bottom of a receptacle, the zinc plate will contact with the bottom of the receptacle at its central portion only, thus exposing the greater surface 65 of the zinc plate and holding the flange 5 out of contact with the bottom of the receptacle. It is to be understood, however, that either of the plates may be provided with the flange 5, and either of the plates 70 may be dished so as to seat on the bottom of the receptacle.

Between the two plates, there is inserted or sandwiched a filling or layer 7 comprising a comminuted or finely granulated or pulverized mixture of aluminum and zinc, or either a mixture of comminuted zinc and 80 salt, and a vehicle or binder therefor of plaster of Paris or its equivalent to hold the zinc and salt reasonably well mixed. This filling, as will be seen, embodies a comminuted anode similar to the anode plate 4. 85 The particular mixture or quality of the mixture depends upon the use to which the appliance is to be put, or in other words, depends upon the strength of galvanic or voltaic current that is required, as will hereinafter appear.

In use, the attached anode and cathode plates are immersed in an electrolyte consisting in a solution of water and salt, preferably in the proportion of one spoonful of 95 salt to one quart of water, and the metallic articles which are to be cleaned are also immersed in conjunction and in contact with the aluminum plate. The salt employed is preferably common table salt, or sodium 100 chlorid NaCl. The immersion of the anode and cathode plates will set up a galvanic or voltaic current within the solution, and the hydrogen or constituents freed or liberated by the electrolytic action attack and 105 remove or dissolve the oxid and sulfid or tarnish from the articles. This oxid or tarnish is quite rapidly removed and leaves the metal articles clear and bright without affecting or stripping the metal due to the 110

electrolytic action. After the articles have been properly cleansed they may be readily removed and dried in any convenient manner. No rubbing or polishing is necessary, and the electrolytic action is the sole action necessary to bring about the result desired.

The present appliance or battery element is adapted particularly for cleaning silverware, although it may be employed for 10 cleaning nickel, gold and other metals.

The filling is advantageous, inasmuch as it serves to strengthen the galvanic current after the appliance has been in use for some time. It is to be understood, therefore, that 15 the quality of the filling 7 may be altered to suit the uses to which the appliance is to be put, or according to other circumstances.

The peripheries of the plates being attached prevents the electrolyte from passing 20 between the edges of the plates and thus prevents local action and corrosion between the edges of the plates, as well as protecting the filling from the action of the electrolyte. The plates in being in direct electrical contact will also reduce to a minimum the local 25 action adjoining the plates, and they may be easily cleansed when not in use. It has been found in practice, that the electrolytic action will cause a film like deposit or coating 30 on the plates, but this may be readily removed with a damp cloth, or with ordinary baking soda if necessary, after the plates have been removed from the electrolytic solution. The plates might also be riveted or 35 otherwise secured together instead of in the manner illustrated and described, but it is found in practice, that if the plates are not peripherally attached so as to exclude the electrolyte from between the edges of the 40 plates, corrosion and local action sets up between the edge portions of the plates, which is disadvantageous. This method of securing the plates together also renders the 45 cleansing of the plates convenient and also renders the device easy to manipulate. The disks being secured together in the manner defined, and containing the filling therebetween including the comminuted anode 50 will provide a comparatively effective electrolytic action or galvanic current, wherein the efficiency would be reduced if the plates were merely in contact but not secured together as described.

Inasmuch as the aluminum and zinc plates 55 have only a comparatively small difference of electric potential, a weak current will be set up when the galvanic pair are immersed in the salt electrolyte, the galvanic current flowing from the aluminum plate through 60 the electrolyte to the zinc plate. However, when the silver, or similar articles to be cleaned, are brought into contact with the aluminum plate, they having a greater ratio 65 of electric potential with respect to the zinc plate than the aluminum plate, the silver

articles will form an anode or electro negative with respect to each of the aluminum and zinc plates, and consequently, but very little current will flow from the aluminum to the zinc plate, and a considerable current 70 will flow from both the aluminum and zinc plates, to the silver articles. Thus, when the galvanic pair are submerged in the electrolyte they will jointly serve as an anode or electropositive, while the silver or similar articles will serve as the cathode, the hydrogen liberated attacking the oxid and sulfid deposited on the silver articles, so as to reduce the same. A further advantage accrues from the employment of aluminum and the zinc plates in combination, it being found in practice, that the aluminum plate 75 will not corrode or become coated as quickly as the zinc plate, and consequently, the aluminum plate will provide a more perfect contact for the articles to be cleaned. It has also been found in practice that the slight coating of the aluminum plate will not appreciably decrease the electrical contact of the metal articles with the aluminum plate, the coating also being readily removed by a damp cloth, which is not possible with the zinc plate. In this connection, it is to be observed that the dished condition of the zinc plate will serve to support the aluminum plate above the bottom of the vessel, and furthermore, the peripheral portions of the zinc plate will be properly spaced above the bottom of the vessel so that they may be attacked by the electrolyte.

Either the aluminum or zinc plate may be employed separately, but it has been found that either of the said plates when in contact with the article to be cleaned and immersed in the electrolyte, will result in a much weaker current, than if the two plates are combined and peripherally attached. It has also been found in practice that when either of the said plates is independently immersed, the chemical action or disintegration of the plate will be general throughout their surface, whereas if the two plates are combined, the corrosion of the zinc plate will be localized, in an annular zone adjoining the periphery of the aluminum plate which 110 is flanged over the periphery of the zinc plate.

The filling between the two plates is of decided advantage, inasmuch as the electrolyte will flow through the plates as they corrode, and will attack the electropositive filling, so as to increase the chemical action, and consequently, to increase the strength of the current. It has also been found, in practice, that as the zinc plate decomposes or corrodes, it will tend to lessen the galvanic current and that the electrolyte will pass through the zinc plate so as to attack the filling to intensify the current. The filling 125 also serves to increase the life of the zinc 130

plate. It is to be understood that the utility of the filling resides particularly in the fact that the device, as a whole, serves as an anode or electropositive when the metal articles are in contact with the aluminum plate. The employment of the filling between the two plates will therefore intensify the galvanic current, and as a result, the oxids and sulfids will be more readily or 10 quickly dissolved from the articles to be cleaned.

The plates may be employed in connection with any suitable vessel, and the silverware, or other metal articles will be cleansed if 15 they are brought into direct contact therewith, or into the electrical connection with the plates, by touching one another.

What is claimed is:—

1. An appliance for cleaning tarnished 20 metal articles comprising peripherally attached electropositive plates, and an electro-positive filling therebetween.

2. An appliance for cleaning tarnished metal articles, comprising a pair of electro- 25 positive plates, the periphery of one being

flanged over the periphery of the other, and an electropositive filling between the plates.

3. An appliance for cleaning tarnished metal articles, comprising peripherally attached electropositive plates, and an electro- 30 positive filling therebetween, one of the plates being dished so as to seat on the bottom of a vessel to space the peripheries of the plates thereabove.

4. An appliance for cleaning tarnished 35 metal articles, comprising a pair of superposed electropositive plates, the marginal portion of the upper plate being flanged over the margin of the lower plate, the lower plate being dished to seat on the bottom 40 of a vessel so as to space the margins of the plates thereabove, and an electropositive filling between the plates.

In testimony that I claim the foregoing as my own, I have hereto affixed my signature 45 in the presence of two witnesses.

HENRY MILTON FETTERS.
